Int. Cl. D8—02

U.S. Cl. D8—65

FIG. 1 is a side view of a chain saw, showing my new design.

FIG. 2 is another side view thereof, showing the side opposite that illustrated in FIG. 1.

FIG. 3 is a top plan view thereof.

FIG. 4 is a bottom plan view thereof.

FIG. 5 is an end view thereof.

FIG. 6 is an end view thereof showing the end opposite that illustrated in FIG. 5.

The broken line representation of a conventional chain in FIGS. 1, 2, 3, 4 and 5 is for illustrative purposes only.

I claim:

The ornamental design for a chain saw, as shown and described.
